FLEXIBLE FAN UNIT

Everett P. Larsh, Vandalia, Ohio, assignor to The
Master Electric Company, Dayton, Ohio, a cor-
poration of Ohio

Application June 13, 1938, Serial No. 213,359

18 Claims. (CL. 170—159)

This invention pertains to electric fans, and more particularly to reinforced blades therefor of flexible or pliable material and the method of manufacture thereof.

Use of non-rigid flexible or resilient fan blades to minimize injury upon contact therewith and to obviate the necessity for enclosure guards has been long known. In some instances these fan elements have been pliable or flexible straps, connected at their ends, and in others the blades are normally limp wings which are distended by centrifugal influence during rotation. In still other embodiments the material of the blades has been impregnated with some stiffening material or the blades have been molded from rubber or other composition in such a way as to render them somewhat self-supporting or resistant. However, these devices have for the most part lacked stability and have been inefficient in use, tending to yield to air resistance and are otherwise objectionable.

The present fan blade structure forming the subject matter hereof is reinforced by a formed metal insert or abbreviated blade of somewhat smaller size, suitably shaped and contoured, which is embedded in the flexible material of the blade to afford sufficient rigidity throughout the major portion thereof to enable it to retain its prescribed shape and inclination or pitch against air resistance, and beyond which the margins and terminal extensions of the blade are sufficiently flexible and resilient that they yield to contact with an interposed obstruction at operating speed, and are sufficiently resilient to be self-restoring when so distorted from normal shape.

The object of the invention is to improve the construction as well as the mode of operation of rotary fan blades, whereby they may not only be economically manufactured, but will be more efficient in use, safe in operation, uniform in action, of sturdy construction, and unlikely to get out of repair.

A further object of the invention is to provide a fan blade having sufficient flexibility to prevent injury in event of accidental contact, wherein the deformation is restricted to a limited area without destroying or materially decreasing the air impelling action of the blade while so deformed or temporarily disturbing its balance to any appreciable degree.

A further object of the invention is to increase the stability of flexible fan blades and provide a maximum effective air impelling area under all conditions.

A further object of the invention is to minimize noise during operation.

A further object of the invention is to assure retention of a prescribed shape and pitch of the blade, minimize the necessary amount of rubber or other flexible material, and reduce the weight of the completed impeller unit.

A further object of the invention is to provide an improved method of mounting the impeller.

10 A further object of the invention is to provide a rotary fan having the herein mentioned advantageous structural features and meritorious characteristics.

15 With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

20 In the drawings, wherein is shown the preferred but obviously not necessarily the only form of embodiment of the invention, Fig. 1 is a side elevation of an electric fan equipped with a rotary flexible rotor or blade unit embodying the present invention.

25 Fig. 2 is a front elevation of the assembled composite rotor or impeller.

30 Fig. 3 is a side elevation thereof.

Fig. 4 is a transverse sectional view through one of the blades.

35 Fig. 5 is a front elevation of the petaliform reinforcement insert or core member.

Fig. 6 is a side elevation of the reinforcement core before embedment in the resilient blade material.

40 Fig. 7 is a radial section through the blades and hub of the impeller.

Fig. 8 is a front view of one member of a sectional reinforcement core.

Fig. 9 illustrates an economical mode of blanking the sections shown in Fig. 8.

45 Fig. 10 is a front elevation of an assembled sectional core.

Fig. 11 is a sectional view of a modification.

Fig. 12 is a detail view of a single blade element.

Fig. 13 illustrates an assembly of separately formed blade elements.

50 Fig. 14 is a detail view of a driving head.

Like parts are indicated by similar characters of reference throughout the several views.

In the drawings, 1 indicates a conventional pedestal and motor housing of a portable elec-

tric fan, the particular shape and detail construction of which are not material to the present invention. Mounted on the motor shaft is the composite impeller or blade unit 2 forming the subject matter hereof. For illustrative purposes the impeller is shown as comprising a group of four radially disposed, internally reinforced blades 3—3. The number of blades and the particular shape thereof may be varied to accommodate the fan to different operating conditions and requirements. The major bodies of the blades 3 may be formed of any suitable pliable or resilient material such as paper, fabric, fiber, or the like, but are preferably molded from soft or semi-soft rubber. While the several blades 3 may be independently formed and subsequently assembled into the unitary impeller 2, the blade assembly is preferably formed as a single integral unit.

Embedded in the impeller is a metallic reinforcement core 4 or insert shown in Figs. 5 and 6, stamped or otherwise formed from sheet metal. The core or insert 4 comprises a plurality of integrally interconnected radially disposed leaves of obovate form, which may be well termed a petaliform insert or core. The fan blades 3, including the leaves or petals of such petaliform insert, embedded therein are transversely curved or of concavo-convex form. In addition to such curvature they are inclined to the common plane of rotation, thus affording a pitch angle commensurate with the desired air impelling action.

Adjacent to the inner ends of the blades at which they are joined to each other, the leaves or petals of the petaliform insert are interconnected by a disc like hub portion. The contiguous portions of the reinforcement leaves are embossed to afford stiffening beads or ribs 5. For illustrative purpose the stiffening beads or ribs have been shown as of arcuate form grouped in spaced relation about the center of the core or insert. They may, however, be otherwise disposed in such relation as will best meet the requirements and conditions of use to which the impeller is to be subjected. Such construction and configuration renders the blades of the impeller sufficiently rigid to maintain its effective pitch angle at all times.

The embossed ribs or beads 5 also serve to materially strengthen the impeller blades at their otherwise weakest points, i. e., their juncture with the hub, to prevent breakage or bending of the blades out of their common plane of rotation. To afford increased anchorage of the rubber or other flexible or pliable material of which the blade is formed and in which the petaliform core or insert is embedded, the latter is provided with a series of holes 6—6, through which the material at opposite sides of the insert is integrally united. These are shown as transverse slots, but may be otherwise shaped, and may comprise a series of spaced round or irregular holes or elongated slots otherwise disposed in each leaf or petal of the unitary insert.

At its center the insert is provided with a hole 7, preferably, although not necessarily, larger than the diameter of the shaft on which the impeller is to be mounted.

During the subsequent embedding operation in which a body of flexible or resilient material is molded or otherwise formed about the insert, the rubber or other enclosing material partially fills such hole 7, uniting through the hole the enclosing material at opposite side of the insert for increased security and thereby reducing the size of the hole to somewhat less than the di-

ameter of the motor shaft on which the impeller or fan blade unit is to be mounted. A group of additional holes 8 are also provided in different radial positions about the central shaft hole 7, the size of which is also reduced in like manner by the extension of rubber or other flexible material therethrough during the molding or embedding operation.

These rubber lined holes 7 and 8 are used to couple the fan blade unit to the motor shaft for unison rotation. Such rubber lining within the holes 7 and 8 provides a flexible, somewhat resilient mounting for the rotor unit which absorbs vibration and minimizes noise. It further enables the rotor to automatically adjust itself within reasonable limits into the plane of rotation if it should become inclined thereto.

The rubber or other flexible covering of the insert may be applied in any suitable manner or customary way. Ordinarily this is performed in a suitable mold under heat and pressure. It is, however, highly important that each of the fan blades shall contain equal amounts of material and that the petaliform insert or core shall be symmetrically located to afford a properly balanced structure.

The dimensions of the blades, both longitudinally and transversely, are greater than those of the insert. The tips of the blades extend a considerable distance beyond the termini of the insert leaves as shown by solid and dotted lines in Fig. 2. Likewise the leading and trailing edges of the blades extend beyond the edges of the reinforcement insert. Such extended portions are sufficiently flexible to yield under impact and permit the extensions of the blades to bend without breakage or permanent distortion. Such portions are sufficiently resilient and possess such degree of inherent rigidity as to be self-restoring and to maintain their pitch angle and radial positions when at rest.

In molding rubber or other embedding material about the insert, the rear sides of the blades are each, preferably but not necessarily, provided with a series of transverse ribs 9 of low altitude as compared with their width. The ribs or beads 9 are of curvilinear form concentric with the axis of the rotor or impeller.

Coincident with the center of the unit there is formed a projecting conoidal hub 10 having therein an axial bore and a series of relatively spaced bores parallel thereto coincident with the holes 7 and 8 of the insert. The hub 10 is integral with the radial blade portions and the latter are made to conform in their curvature and pitch to those configurations of the insert. The insert may be embedded in the enclosing rubber or other flexible body while flat and the blades subsequently shaped to the proper curvature and pitch inclination. However, the preferable method is to contour the insert leaves to their final shape before embedment and thereafter mold the rubber or like material thereabout into agreement with the blades or leaves of the pre-formed insert.

By such construction strains and stresses in the rubber cover as well as in the insert are avoided and the material may be more uniformly distributed. The extensions of the rubber blades beyond the limits of the insert, as indicated in Fig. 2, provides flexible terminals and also flexible leading and trailing edges which extend considerable distances beyond the peripheries of petal or leaf sections of the insert and which will yield upon impact engagement with an object

without injury to either the blade or the object and will resume their original shapes when free therefrom. The provision of the reinforcement insert and the embossing of the central portion thereof affords such construction and configuration as to maintain the pitch angle and concavo-convex contour of the fan blades under all conditions. The reinforcement insert becomes an integral component of the final impeller structure and an inherent part of each blade thereof, rendering the blades self-supporting and amply rigid throughout the inner radial portions thereof to perform their air impelling functions while the outer terminal and edge portions may be distorted. The inner portions of the blades are of such construction and configuration that the blades are sufficiently rigid to maintain substantially radial positions at all times.

While the holes 8 of the reinforcement core element in the finished impeller provide torsional driving connection with a driving head 11 mounted on a drive shaft 12 and having correspondingly spaced studs 13 engageable in the bores 8', the holes 8 also serve during the construction of the impeller to properly locate the core member in the mold in symmetrical relation therewith while the rubber is being molded thereabout. The rubber mold is provided interiorly with a group of studs corresponding to the studs 13 which in the finished product afford the spaced bores 8', and over which the reinforcement core is positioned with such locating studs engaging in the holes 8 thereof. Such locating use is additional to the driving function of the holes. In the event that the impeller is of small size or not subject to great load, it may be frictionally engaged upon the drive shaft 12 by merely pressing the shaft into the central bore 1 without use of driving studs 13 to engage the bores 8'. The bore 1 being of somewhat smaller diameter than that of the shaft, the contiguous rubber material is subjected to expansive tension causing the shaft to be firmly gripped by the rubber hub.

While the reinforcement core is illustrated and described as comprising multiple integrally interconnected leaves, it may be assembled from separately formed elements consisting initially of either single or double leaf elements united by welding or riveting or otherwise, or such independent reinforcement elements or inserts may be separately embedded in the enclosing body of rubber and flexibly inter-connected by the contiguous portions of rubber.

The single integral reinforcement insert 4 having integral radially disposed leaves cannot be blanked from the sheet material without considerable waste. However, if the reinforcement insert leaves are formed in pairs as shown in Fig. 8, they may be more economically blanked as illustrated in Fig. 9 with minimum waste of material.

Such separately formed elements, each comprising a pair of oppositely disposed leaves 4 and an intermediate interconnecting hub portion, may be disposed in transverse relation as shown in Fig. 10 and united by welding or by riveting.

In lieu thereof it is quite practical and desirable for some conditions of use to have succeeding blades of the completed impeller flexibly connected for a limited yielding movement relative to each other. This is especially desirable for use under conditions where fingers may be extended into the path of rotation of the blades. Upon contact with an intercepting finger or other object the engaging blade would slightly yield and

would not be subject to the full momentum or inertia of the impeller. Such construction would possess a slight shock absorbent characteristic under such circumstances. By supporting two of the separately formed units in the rubber mold in slightly spaced relation with each other and embedding them in a single body of rubber or the like, such yielding effect of one reinforced blade relative to another may be achieved. In Fig. 11 such relation of separate reinforcement or insert elements flexibly connected is illustrated. If so desired, each reinforcement leaf may be separately formed and indeed separately embedded in rubber for assembly side by side on a drive shaft. In Fig. 12 there is shown one such single reinforced flexible blade element, and in Fig. 13 a series of such individual flexible reinforced blades are shown assembled in cooperative relation on a drive shaft. Such assembly may consist of two, three or any greater number of blade elements. Such members agree generally in form and construction with those previously described, including a similar insert leaf 4 and integral hub portion embedded in a flexible rubber felt or composition blade of greater size, including a rubber hub portion.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A fan element including a hub portion and a plurality of integrally united blades molded to shape from rubber, a unitary metallic petaliform core member of sheet metal reinforcing the hub and inner radial end only of each blade, the outer radial portion of each blade being free from any reinforcement and being sufficiently soft and flexible to yield upon engagement with an object and having capacity to resume its shape when free from the object.

2. A fan element presenting a petaliform core portion of sheet metal and rubber covering the core member and extending radially considerably beyond the periphery of each of the petal sections of the core member, thereby providing a rubber fan in which each blade is interiorly reinforced at its inner radial end and the outer radial portion of which is soft and flexible.

3. A fan element having a petaliform core portion of sheet material and rubber enclosing each petal section of the core portion to form the blades of the fan and also enclosing the central part of the core portion, said rubber having considerable thickness at said central part of the core thereby to form a rubber hub for the fan, the rubber portion of each blade extending radially considerably beyond the periphery of its petal section of the core to provide

an outer radial portion for the blade which is sufficiently flexible to yield when it engages an object but which is capable of resuming its normal shape when free from said object.

4. A fan element having a petaliform core portion and rubber enclosing each petal section of the core portion to form the blades of the fan and also enclosing the center of the core portion and forming a rubber hub for the fan, the rubber portion of each blade extending radially considerably beyond the periphery of its petal section of the core to provide an outer radial portion for the blade which is sufficiently flexible to yield when it engages an object but which is capable of resuming its normal shape when free from said object, said rubber hub portion of the fan element having an axial shaft-receiving opening.

5. A fan element comprising a hub and blades formed of rubber and a petaliform core member of sheet material embedded in and entirely enclosed by the rubber with a petal section of said core located at and reinforcing the inner radial end only of each blade, the outer radial portion of each blade being free from reinforcement and being self-sustaining but sufficiently flexible to yield when engaged by an object and capable of resuming its normal shape when free from said object.

6. A fan element presenting a petaliform core portion of sheet metal, the petal sections of which have a pitch angle corresponding to the pitch angle required in each blade of the fan and an integral rubber portion which covers the core portion and forms both a rubber hub for the fan and the blades thereof, the rubber part of each blade extending radially considerably beyond the periphery of the petal section thereof and normally having a less pitch angle than that of the corresponding petal section, the rubber portion of each blade being held in distorted condition at said required pitch angle of the blade by the corresponding petal section of the core, the outer radial portion of each blade being sufficiently flexible to yield when it engages an object but being capable of resuming its normal shape when free from said object.

7. A fan comprising a hub, radially projecting blades carried thereby, and a petaliform reinforcement insert embedded interiorly thereof, said blades being formed at their outer portions of material sufficiently flexible to bend readily without permanent distortion, and the inner end portions of said blades being of a construction and configuration such that said blades are sufficiently rigid to maintain a substantially radial position at all times.

8. A fan comprising a hub, radially projecting blades carried thereby, and a petaliform reinforcement insert embedded interiorly thereof, said blades being formed at their outer portions of material sufficiently flexible to bend readily without permanent distortion, and the inner end portions of said blades being of an obliquely curved configuration and a construction such that said blades are sufficiently rigid to maintain an effective pitch angle upon rotation.

9. A fan comprising a hub, radially projecting blades formed of material sufficiently flexible to bend readily without permanent distortion, and a petaliform reinforcement of less extent than the blades embedded interiorly thereof, the inner end portions of said blades being maintained sufficiently rigid by said hub and of a configuration to increase the resistance of said blades to axial

thrusts without materially increasing their resistance to deformation upon encountering an object in their path of rotation.

10. In a fan, a hub, a plurality of flexible rubber blades, and a petaliform reinforcement means embedded interiorly thereof and coacting with said hub and base portions of said blades to maintain said blades in a self-sustained radial position on said hub oblique to the axis of rotation, said blades being sufficiently flexible and resilient to be self-restoring after striking an object in its path of rotation and of sufficient rigidity to substantially maintain a pitch angle upon rotation effective for air delivery.

15. In a fan, a hub, rubber blades, and a petaliform reinforcement member embedded within and engaging portions of said blades for maintaining them in a normally radial and substantially cupped position on said hub, said blades being of such flexibility and resilience as to be self-restoring upon distortion from normal position and of sufficient rigidity when assembled to substantially maintain a predetermined pitch position on the hub.

20. 12. A fan comprising a hub, radially projecting blades carried thereby, said blades being formed of material sufficiently flexible to bend readily without permanent distortion, and a petaliform reinforcing member embedded in the inner end portions of said blades of a construction and configuration such that said blades are sufficiently rigid to substantially maintain their pitch angle upon rotation, and said blades being relatively wide with respect to their radial dimension.

25. 13. A fan comprising a hub, radially projecting blades carried thereby, said blades being formed of a material sufficiently flexible to bend readily upon striking an object without permanent distortion, and a petaliform reinforcing element embedded in the inner end portions of said blades, of a construction and configuration such that said blades are sufficiently rigid to maintain an effective pitch angle at all times.

30. 14. A rotary fan impeller including a plurality of radially disposed blades of flexible material and a centrally disposed conoidal hub therefor of like material formed integrally with the flexible material of the blades, and a unitary reinforcement insert comprising multiple interconnected radially disposed leaves of strain resistant material, one leaf of which is embedded in each blade thereof of the impeller and a central portion of the insert integrally connecting the leaves one with another and embedded in the conoidal hub of the impeller, said hub and insert having registering openings therein for connection of the impeller with a drive mechanism.

35. 15. A fan element including a petaliform reinforcement core comprising initially plural sections fixedly interconnected with each other and a rubber covering in which the reinforcement core assembly is embedded, said covering extending beyond the periphery of each section of the core, thereby providing a fan element in which each blade is interiorly reinforced at its inner radial end and the outer radial portion of which is soft and flexible.

40. 16. A fan element including a petaliform reinforcement core comprising plural separate sections and a rubber covering in which the reinforcement core sections are embedded and by which they are yieldingly connected with each other, said covering extending beyond the periphery of each section of the core thereby pro-

viding a fan element in which the blades are inferiorly reinforced at their inner radial ends and the outer portions of which are soft and flexible, the blades being yielding in relation one to another in the plane of rotation.

17. A fan element including plural separate reinforcement core sections disposed in petaliform relation, a rubber covering in which each core section is embedded, said covering extending beyond the periphery of the enclosed reinforcement core section thereby providing a plurality of separate fan blades each of which is inferiorly reinforced at its inner radial end and the outer radial portion of which is soft and flexi-

ble, and a hub portion upon each blade by which the blades may be assembled in radiating relation side by side on a common shaft.

18. As an article of manufacture, a reinforcement insert for a rubber fan element, comprising a single integral petaliform member formed from sheet material including a plurality of radially disposed leaves and a central interconnecting hub portion and a plurality of spaced locating holes in said member for engagement of locating studs for positioning the insert in a mold to receive a body of embedding material and embossed areas on the member to stiffen such portions thereof.

EVERETT P. LARSH.
